UNITED STATES PATENT OFFICE.

GEORGE BULL, OF LEEDS, ENGLAND, ASSIGNOR TO HENRY BERRY AND COMPANY LIMITED, OF LEEDS, ENGLAND.

EXTRUSION PRESS FOR FORMING RODS AND THE LIKE FROM METAL BILLETS.

Application filed June 14, 1924, Serial No. 720,005, and in Great Britain January 17, 1924.

This invention relates to that type of extrusion press in which the metal of a billet carried in a container is extruded through a die to form a rod or the like (hereinafter termed "rod") by effecting relative movement between the said container and the said die.

Hitherto, the die has been located apart from the container and formed on or fixed to the lower end of a stationary tubular member, the said container being closed at its lower or rear end and the billet passed thereinto by way of its open upper or forward end prior to effecting the extrusion stroke.

Now the object of this present invention is to provide an improved extrusion press, as hereinafter described, for forming rods from metal billets, whereby the extrusion defects due to skin friction are reduced to a minimum and the power required to extrude the rod is substantially lessened.

In an extrusion press according to this invention for forming rods from metal billets, the die and metal billet are passed into a container by way of its open rear end until the die comes to rest against the rear end of a stationary tubular plunger projecting into the forward end of said container and the open rear end of the container is then sealed and the sealed container moved forwardly upon the stationary tubular plunger so as to extrude the metal of the billet through the stationary supported die to form a rod.

In a convenient form of construction, the die and metal billet are first moved together forwardly into the container by a pusher bar until the die comes to rest against the rear end of a stationary tubular plunger projecting into the forward end of said container, the open rear end of which is now sealed by a gag piece and the sealed container moved forwardly upon the stationary tubular plunger so as to extrude the metal of the billet through the stationary supported die to form a rod which is projected forwardly through the stationary tubular plunger during the forward travel of the sealed container. The forward travel or extrusion stroke of the sealed container is such as to leave a residual piece of metal on the rear end of the formed rod, and after such extrusion stroke the container minus its gag piece is moved further forward upon the stationary tubular plunger so as to leave the

residual end of the rod clear of the rear end of the container to enable the residual piece of metal to be removed from the formed rod and the latter to be drawn out from the press.

The invention will now be described with reference to the accompanying drawings; wherein:

Figs. 1 and 2 are respectively a sectional plan view and a part sectional side elevation of a hydraulic extrusion press in accordance with this invention; while Figs. 3 to 12 inclusive are sectional plan views of a part of the same press illustrating the various stages in the manufacture of a rod.

Referring particularly to Figs. 1 and 2 of the drawings, 1 is a receiver, 2 the die, 3 the metal billet, 4 the container, 5 the pusher bar, 6 the stationary tubular plunger, 7 the gag piece, 8 double-acting rams, 9 a main ram, 10 clamps, 11 draw-back rams, and 12 a saw.

Referring now particularly to Figs. 3 to 12 of the drawings, the die 2 and the metal billet 3 are first placed in the receiver 1 (Fig. 3), when the receiver 1 is moved transversely so as to bring the die 2 and metal billet 3 into alignment with the container 4 (Fig. 4), after which the die 2 and metal billet 3 are together moved forwardly by the pusher bar 5 into the container 4 until the die 2 comes to rest against the rear end of the stationary tubular plunger 6 which projects into the forward end of said container 4 (Fig. 5), whereupon the pusher bar 5 is withdrawn and the gag piece 7 moved transversely so as to bring it into alignment with the open rear end of the container 4 (Fig. 6). The container 4 is now moved rearwardly through the medium of the double-acting rams 8 up against the gag piece 7 so as to seal the open rear end of the said container 4 (Fig. 7 and also Fig. 1), when the sealed container 4 is moved forwardly upon the stationary tubular plunger 6 by the main ram 9 so as to extrude the metal of the billet 3 through the stationary die 2 to form a rod 3^x which is projected forwardly through the stationary tubular plunger 6 during the forward travel of the sealed container 4, the stroke of the main ram 9 being such as to leave a residual piece of metal 3^y on the rear end of the formed rod 3^x (Fig. 8). The double-acting rams 8 now move the container 4 further forward upon the stationary tubular plunger 6 so as to leave the residual piece 110

of metal 3^y of the rod 3^x clear of the rear end of the container 4 (Fig. 9), when the gag piece 7 is moved transversely so as to bring the clamps 10 into alignment with the 5 residual piece of metal 3^y on the rear end of the rod 3^x (Fig. 10), after which the clamps 10 are moved forwardly by the main ram 9 and screwed up upon the residual piece of metal 3^y on the rear end of the rod 3^x (Fig. 10 11), whereupon the clamps 10 and parts associated therewith are moved rearwardly by the draw-back rams 11 so as to withdraw the residual piece of metal 3^y together with the rod 3^x and die 2 rearwardly clear of the 15 container 4 (Fig. 12). The saw 12 is now lowered and the formed rod 3^x severed thereby from the residual piece of metal 3^y, when the formed rod 3^x is free to be drawn out forwardly from the press by way of the 20 stationary tubular plunger 6.

What I claim as my invention and desire to secure by Letters Patent is:—

1. An extrusion press of the type specified for forming rods from metal billets, comprising in combination a billet container open at its rear end, a stationary tubular plunger projecting into the forward end of the container, a die for the container, means for inserting the die and a metal billet forwardly into the container by way of its open rear end until the die comes to rest against the rear end of the stationary tubular plunger, this operation taking place without any extrusion of the billet occurring, means for 25 sealing the open rear end of the billet container, and means for moving the sealed container forwardly upon the stationary tubular plunger so as to extrude the metal of the billet through the stationarily supported die to form a rod. 30

2. An extrusion press of the type specified for forming rods from metal billets, comprising in combination a billet container open at its rear end, a stationary tubular plunger projecting into the forward end of the container, a die for the container, a pusher bar for inserting the die and a metal billet together forwardly into the container by way of its open rear end until the die comes 45 to rest against the rear end of the stationary tubular plunger, this operation taking place without any extrusion of the billet occurring, a gag piece for sealing the open rear end of the billet container, and means 50 for moving the sealed container forwardly upon the stationary tubular plunger so as to

to extrude the metal of the billet through the stationarily supported die to form a rod which is projected forwardly through the stationary tubular plunger during the forward travel of the sealed container. 60

3. An extrusion press of the type specified for forming rods from metal billets, comprising in combination a billet container open at its rear end, a stationary tubular plunger projecting into the forward end of the container, a die for the container, a pusher bar for inserting the die and a metal billet together forwardly into the container by way of its open rear end until the die 70 comes to rest against the rear end of the stationary tubular plunger, this operation taking place without any extrusion of the billet occurring, a gag piece for sealing the open rear end of the billet container, and means for moving the sealed container forwardly upon the stationary tubular plunger so as to extrude the metal of the billet through the stationarily supported die to 75 form a rod and leave within the sealed container a residual piece of metal on the rear end of the formed rod. 80

4. An extrusion press of the type specified for forming rods from metal billets, comprising in combination a billet container open at its rear end, a stationary tubular plunger projecting into the forward end of the container, a die for the container, a pusher bar for moving the die and a metal billet together forwardly into the container 85 by way of its open rear end until the die comes to rest against the rear end of the stationary tubular plunger, a gag piece for sealing the open rear end of the billet container, means for moving the sealed container forwardly upon the stationary tubular plunger so as to extrude the metal of the billet through the stationarily supported die to form a rod and leave within the sealed container a residual piece of metal on the 90 rear end of the formed rod, and means for moving the container minus its gag piece further forward upon the stationary tubular plunger so as to leave the residual end of the rod clear of the rear end of the container, together with means for removing the residual piece of metal from the formed rod to enable the latter to be drawn out 95 from the press. 100

In witness whereof I have hereunto set my hand. 110

GEORGE BULL.
